UNITED STATES PATENT OFFICE.

JOHN C. ENGSTRAND, OF CHICAGO, ILLINOIS.

RAILWAY-CROSSING.

1,180,766.

Specification of Letters Patent. Patented Apr. 25, 1916.

Application filed July 2, 1915. Serial No. 37,698.

To all whom it may concern:

Be it known that I, JOHN C. ENGSTRAND, a citizen of the United States of America, residing at Hegewisch, Chicago, in the county 5 of Cook and State of Illinois, have invented certain new and useful Improvements in Railway-Crossings, of which the following is a specification.

The present invention relates to improvements 10 in railway crossings, and is designed particularly to provide an automatically closing joint that may be opened by the passage of the passing car wheels and which is practically noiseless and presents a smooth 15 track for the wheels to pass over.

The invention consists in certain novel combinations and arrangements of the guard rails and crossing rail joints as will be hereinafter more fully pointed out.

20 In the accompanying drawings I have illustrated one complete example of the physical embodiment of my invention constructed according to the best mode I have so far devised for the practical application 25 of the principles of my invention.

Figure 1 is a plan view of one of the four corner joints. Fig. 2 is a side view of Fig. 1 showing a portion of a rail in section. Fig. 3 is a diagrammatic plan view of the crossing constructed according to my invention. 30 Fig. 4 is a section on line 4-4 of Fig. 3. Fig. 5 is a section on line 5-5 of Fig. 3. Fig. 6 is a perspective view in detail showing the connection between two crossed 35 guard rails.

In the diagrammatic view of Fig. 3 I have illustrated a crossing comprising the four joints A, B, C, D, which are connected by the rail sections or bars E, E', E² and E³ 40 respectively while the track rails are designated by the letters F, F, and G, G, the whole being intended to exemplify a single track crossing adapted for use especially in connection with railways of the street type. 45

Inasmuch as each of the four joints A, B, C, D, are duplicates of each other I have decided to refer specifically to the joint A in my detailed description of the invention.

Each of the four joints is built upon a 50 base plate of cruciform shape comprising the four arms 1, 2, 3, and 4. These arms are each slotted as at 4' and the usual rail heads are omitted from the arms, but the heads of the sections F, G, E, E', E² and E³ are substituted therefor, while the webs E⁴ of the connecting sections and the webs F' of the

rails F and similar webs of the rails G fit neatly into these slotted arms and the webs are attached to the arms by means of the bolts 5 and nuts 6, as usual. The bases of 60 the connecting rails E E' E² E³, and the bases of the rails F and G where they are coupled with the arms of the base plate, are omitted from these rail sections, but these bases are supplied by the cruciform castings as shown.

In connection with each joint A, B, C, D, a pair of angularly disposed guard rails are employed as indicated by the numerals 7 and 8. Each of these rails is disposed alongside the track rails, and the crossed rails each extend to each side of the track rails that it intersects, and at the joint the guard rails are in contact with the track rails. Each of the guard rails is pivoted to swing 75 laterally away from its adjacent track rail, and for this purpose the guard rails are provided with three pairs of perforated lugs, two pairs at the ends and a pair in the center of the rail and indicated respectively 80 as 7' and 8'. These pairs of perforated lugs 7' and 8' each having a corresponding perforated lug 9 integral with the arms of the cruciform base plate, and the lugs on the lower or bottom edge of the guard rails are 85 hinged to the lugs on the bases of the arms of the base plate by means of bolts 10 and secured by the nuts 11. These guard rails are adapted to be turned laterally and downwardly on their hinges by the passage of the 90 wheel flange as the car moves over the crossing, but by means of the bolts 12 which are passed through transverse openings in the webs, and arms of the base plate, and a spring 13 and nut 14 on the bolt 12, the 95 guard rails are returned to normal position as shown in the drawings. There are two return springs for each guard rail, and three hinge supports for each rail, so that they are held in stable and symmetrical relation 100 to the track rails.

In order that the crossed rails 7 and 8 may swing or turn down they are provided with central slots or notches as 15 and 16 respectively so that, as clearly seen in Fig. 105 6, the guard rail 8 may swing to the right without interference from the rail 7, and the rail 7 may swing to the left without interference from the rail 8. To reinforce and brace the joint between these crossed 110 rails I provide them with angular lugs as 7^a and 8^a respectively, and the outer face

of these lugs is struck from a line with the hinge bolts 10 as a center. Each of these lugs is alined with the track that it intersects, and the connection rails or sections 5 E E' E² and E³ have their ends 17 rounded at the underside of their heads so that these lugs may turn down under the ends. At 10 7^b and 8^b the lugs 7^a and 8^a are slotted so that they may fold down past the ends of the webs E⁴, as indicated in Figs. 4 and 5, and this arrangement of parts further adds 15 to the stability of the devices.

In operation, assuming a car to be passing over the crossing from left to right in Fig. 15 3, the flanges of the wheels will engage the guard rails 7, 7 and turn them both inwardly and hold the rails in this position until the wheels have passed through the joint, when the rails are turned back to normal position by the springs 13. The second 20 pair of rails 7 is now encountered by the wheels and they are also turned inwardly, and after passage of the wheels, are returned by their springs 13. It will be noted 25 that the track from left to right is continuous and smooth and the wheels travel over a continuous surface, as the gaps are closed and filled on the track over which the wheels are to pass. In this manner the objectionable features of noise and wear are avoided 30 in the crossing of cars, and the guard rails after being opened by the car wheels and held so until the wheels pass, are automatically returned to normal closed position. All parts

of the rail sections are close fitting, as seen 35 in Figs. 2, 4 and 5, and the tops of the rails or rail heads form a continuous and smooth surface for the wheels to travel over.

What I claim is:—

1. The combination in a rail crossing with 40 four corner base plates and rail sections connecting them, of a pair of crossed guard rails hinged at the sides of the crossing arranged in pairs parallel with the intersecting rails and adapted to be turned down on 45 their hinges, and means for holding the guard rails in normal upright position.

2. The combination with a cruciform shape base plate, of a pair of notched and crossed guard rails each respectively hinged 50 to the base plate at the sides of the corner and adapted to be turned down flat, bolts passed through perforations in the rails and base plate, and springs held on said bolts to 55 return the guard rails to normal upright position.

3. The combination with a cruciform base plate of a pair of notched and crossed guard rails separately hinged to the base plate and each formed with a projecting lug formed 60 with a circular face adapted to co-act with the rail that the guard rail intersects, and means for holding the guard rails in normal position.

In testimony whereof I affix my signature.

JOHN C. ENGSTRAND.
